ELECTRIC EYELET AND GROMMET
MACHINE

George T. Biggs, St. Paul, Minn., assignor, by
mesne assignments, to Jacob Backer, St. Paul,
Minn.

Application October 27, 1930, Serial No. 491,472

9 Claims. (Cl. 218—15)

My invention relates to an electric eyelet and grommet machine adapted to be operated automatically to place the eyelet in the member such as in curtains and curtain sticks and the like, 5 the eyelet and grommet machine operating to punch the hole and fasten the rivet in an automatic operation.

The invention also includes the method of supplying rivets for the machine in a magazine 10 which is adapted to support the rivets or eyelets in the magazine member ready to be used in the eyelet and a grommet machine. The magazine member is separable from the eyelet machine and is supplied with the eyelets in operative position therein. Thus when the eyelet machine is in need of more eyelets it is only necessary to supply a new magazine or cartridge member filled with eyelets which is placed in working position in the eyelet machine 15 so as to direct the eyelets through an eyelet slide or track to the position in which they are inserted for riveting in place. The method of supplying the eyelets consists in placing the eyelets in a channel guide to form the magazine or cartridge, 20 then bending a shoulder in the path of the channel guide on each end thereof to provide a cartridge or magazine filled with eyelets which acts as an eyelet support and guide when the same is placed in my eyelet machine, the shoulder on one 25 end of the cartridge being bent back to release the eyelets before the cartridge or magazine is placed in the eyelet machine.

It is also a feature of my automatic electrically operated eyelet setting and riveting machine to 30 provide means for operating the same through a complete operation of punching the hole for the eyelet, placing the eyelet in the hole and riveting the same, all of which operation is automatic, being carried out by an electric motor which 35 starts the machine to operate on pressing a button to close the circuit to the motor after which a switch operates to keep the circuit closed until the machine has completed the operation of punching the hole and placing a rivet therein and 40 riveting the same, whereupon the circuit is broken to the operating motor and the same stops automatically.

My machine includes an automatic centering gauge which operates to center the curtain stick 45 in relation to the punch and riveting means, thereby providing an eyelet machine which is automatic in its operation as well as in centering of the curtain stick which is to be furnished with an eyelet placed in the center for the curtain cord. With this construction various size cur-

tain sticks may be quickly eyeleted by placing the same in the automatic centering gauge which is carried by the front of the eyeleting machine and pressing the button, and the eyelet machine automatically operates to place the eyelet in the curtain and stick. My electric eyelet and grommet machine illustrated as for use in placing eyelets in curtain sticks in the furnishing of the curtain for the cord, however, it will be apparent that the same structure and with its operating parts may be used for placing grommets or other similar articles or rivets, or in fact, placing eyelets in other than curtain sticks, and the like.

These features, together with other details and objects of the invention will be more fully 10 and clearly set forth in the specification and claims.

In the drawings forming part of this specification:

Figure 1 is a plan view of my electric eyelet 20 and grommet machine.

Figure 2 is a detail of the automatic centering means for curtain sticks and the like.

Figure 3 is a side elevation of my automatic 25 electric eyelet and grommet machine.

Figure 4 is a diagrammatic detail of some of the operating parts in the operation of the punch lever cam.

Figure 5 is a diagrammatic detail of some of the operating parts of the operation of the rivet- 30 ing shaft and lever and cam.

Figure 6 is a diagrammatic detail of the automatic switch and operating cam which controls the operation of the machine.

Figure 7 is a sectional detail longitudinally 35 through a portion of the machine, the upper and front part of which is broken away.

Figure 8 is a front view of the electric eyelet 40 and grommet machine, with the centering means for curtain sticks removed.

Figure 9 is a detail portion of the eyelet setting punch.

Figure 10 is another view in the opposite direction to Figure 9 of the eyelet setting punch.

Figure 11 is a detail of a portion of the punch 45 plunger and operating sleeve.

Figure 12 illustrates one of the eyelet magazines.

Figure 13 illustrates a diagrammatic view of the wiring for controlling the motor which operates my electric eyelet machine.

The automatic electric eyelet and grommet machine is formed with a bed 10 upon which the motor A is mounted on the sliding carriage or plate 11 so that the motor may slide with 55

certain of the operating mechanism during the operation of the eyelet machine.

The eyelet punch and setting mechanism B is also supported upon the sliding plate 11 and is adapted to be operated by the operating shaft 12 of the motor which is keyed to the connection 13 by the pins 14. The connection 13 operates the worm gear 15 which in turn operates the gear 16 which is mounted upon the shaft 17.

- 10 The shaft 17 is carried by the yoke bracket 18 which projects on either side of the gear 16 and which is held by the bolts 19 to the head frame 20 which supports the punch plunger 21 and operating sleeve 22 and which is secured to the carriage 11 in any suitable manner. This head frame also supports the eyelet setting plunger 23. These plungers are operable to reciprocate up and down in the operation of the eyelet machine so as to punch the hole and set the eyelets at the proper time. The sliding plate or carriage 11 operates to move the punch and the plungers for the eyelet setting to the proper positions in the course of operation. This operation will be hereinafter more fully described.

25 The motor A operates through the gear 15 to operate the gear 16 which in turn is adapted to operate the cam 24 which is carried on the shaft 17 by means of a sleeve 25 integral with said cam and which is held adjustable on the shaft by the set screw 26. This cam 24 when rotated clockwise as viewed in Figure 4 engages the punch lever 27 which is normally held with the end 28 engaging with the cam by means of the coil spring 29 one end of which is fastened to the lever 27 and the other end of which is secured to slide 11. The lever 27 is pivoted to the side of the head frame 20 at 30 and the end 31 opposite to the end 28 carries a forwardly projecting operating end 32 which engages in a slot 33 formed in the side of the punch plunger 33. The punch plunger slidably operates within a sleeve 34 and the sleeve 34 reciprocates up and down within the ends 35 and 36 of the head frame 20. A punch anvil 37 is carried by the lower portion of the head frame and projects forward in line with the portions 35 and 36 so that the punch plunger and sleeve operate above and upon the same. The operation of the sleeve 34 will be hereinafter more clearly defined.

50 My automatic eyelet machine is provided with the operating lever 38 which is mounted on the shaft 30 on the opposite side of the head 20 to the lever 27. This lever 38 is formed in two parts, the forward portion 39 of which extends with an offset portion 40 extending under the upper arm 35 of the head 20 and carrying a plate 41 which engages in a slot in the side of the eyelet setting plunger 23. See Figures 4 and 5. When the lever 38 is operated it is adapted to reciprocate the eyelet plunger 23.

65 The plunger 23 is hollow and carries the eyelet mandrel 42 within the same and the lower end of which is slotted at 43 on either side. The nose of the mandrel 42 is rounded at 44 and a hole 45 extends through the mandrel remote from the rounded nose 44. A small spring 46 is adapted to extend along in the recesses or slots 43 along the side of the mandrel 42 and through the hole 45. The ends of the spring 46 are bowed at 47 to project slightly on either side of the rounded nose portion 44 of the eyelet mandrel 42. See Figures 9 and 10. Thus the mandrel 42 is provided with means, through the spring 46, for picking up the eyelets 48 when

the eyelet setting plunger 23 is forced down by the lever 38. The eyelets 48 are held by the magazine member 49 which is in the form of a channel having inturned longitudinal edges 50 and the magazine 49 forms a means of holding the eyelets ready to be dispensed into the eyelet machine when desired. The magazine 49 is formed with end stops 51 so as to normally hold the eyelets 48 in the magazine. When an eyelet magazine 49 is to be inserted in the eyelet machine, one of the stops 51 is bent or broken off and the eyelet magazine 49 is inserted in the guide 52 carried by the side of the head which projects from a suitable supporting standard 53 extending up from the bed 10. The guide 52 is formed to carry the eyelets directly under the eyelet setting plunger 23. Thus eyelets are picked up by the mandrel 42 when the punch 54 which is carried by the end of the punch plunger 33 is in the operation of punching through a curtain stick C which is held in position in the eyelet machine in a manner which will be hereinafter described.

The mandrel 42 of the eyelet setting plunger 23 is held in normal downward position by a coil spring 55 which is positioned within the upper end of the eyelet setting plunger 23 and which is held by the cap screw 56 in the top of the eyelet setting plunger in place so as to bear against the top end of the eyelet mandrel 42. The mandrel 42 extends substantially above the position of the offset portion 40. When the lever 38 moves down to set the eyelet in the hole in the stick C after the hole has been punched in the stick, the end plate 41 is adapted to force the outer or sleeve portion of the eyelet setting plunger 23 down to rivet the eyelet on the eyelet mandrel riveting surface 57, the coil spring 55 allowing the mandrel 42 to slip up into the eyelet setting plunger or sleeve 23 so as to release the mandrel 42 from the eyelet which is being riveted in the stick C.

In the operation of the eyelet setter the ends of the curtain stick C are rested in the pockets 58 of the equalizing or centering means D. The 45 pockets 58 are slidably supported on the arms 59 which operate between the guide rolls 60. The equalizer is attached by the plate 61 to the front end 62 of the eyelet machine so as to hold the curtain stick C in proper position in relation to 50 the mandrel 37.

In placing the stick C in the pockets 58, the pockets 58 may be moved together by means of the chains 63 and 64 which operate over two pair of sprockets 65 and 66 which are carried by the 55 shafts 67 and 68. The pairs of sprockets 65 and 66 are positioned adjacent each other near the center of the equalizer D. The chain 63 has one end secured at 69, while the other end is secured at 70 to the arm 59, while the chain 54 has one end secured at 71 to the other adjacent arm 59 and the other end secured at 72 to the same arm 59. Movement of one of the arms 59 moves the chain 63 which rotates the sprockets 65 and 66. The chain 64 on the adjacent arm 59, passing over the sprockets 65 and 66 on the opposite sides thereof, pulls the attached arm in the opposite direction an equal distance. Thus when the curtain stick C is placed in the pockets 58 and either of the pockets are moved toward or away from each other, the stick C will be automatically properly centered in relation to the punch 54 and the eyelet plungers 23 so that the stick C will be punched exactly in the center and the eyelet may 70

be placed centrally between the ends of the stick, all of which operation is virtually automatic in setting the eyelet in a curtain stick C. Where grommets or other articles are adapted 5 to be set by my machine the centering means D may not be desirable or necessary.

I provide a curtain stick holding or clamping means which includes a pair of rubber covered rests 73 which are positioned on either side of the 10 operating head 20 and supported from the base 10 by the standards 74. Co-operating with the rests 73 I provide a pair of rubber covered clamping fingers 75 which are carried by the arms 76. The arms 76 are pivoted to the base 10 at 77. 15 These arms are formed in two parts, having a rear end 78 which is held on the pivot 77 and by the set screw 79 which operates in a slot to adjust the working end 80 of the arm 76 so that when the end 80 is operated by a cam 81 which 20 is carried by the shaft 17 the arms 76 will operate to clamp the curtain stick against the rest 73 and the fingers 75, each of which are covered with rubber or other cushioning means so as to prevent injury to the curtain stick or the curtain 25 covering which goes around the stick in the making of curtains. In this manner I provide an automatic clamping means which engages the curtain stick after it has been set in the proper position in the centering means D so that when 30 the motor A is operated, the cam 81 will operate the lever 76 to clamp the stick C and hold it firmly until it has been punched and eyeleted and the punch has been removed from the stick, all of which operation is automatic and which 35 will be more clearly hereinafter set forth. A cam 81 engages the end 82 of the rear end 78 of each arm 76 during the punching operation.

The lever 39 operates the eyelet setting plunger or sleeve 23 and the mandrel 42 and the rear portion 82 of this lever is adjustable in relation to the remainder of the lever 39, pivoting on the shaft 30. The lever end 40 is formed with an outwardly projecting boss 83 which projects above a boss 84 which is carried by the lever portion 82. 45 Then by means of a set screw 85 carried by the boss 83 the two boss portions 83 and 84 are adjustably connected together, the set screw 85 being readily adjustable to set the two portions 40 and 82 of the lever 38 in relation to each other. 50 Further, the lever portion 82 is formed with an overlying portion 86 which carries an adjusting screw 87. The overlying portion 86 of the portion 82 of the lever 38 extends over the rear portion of the part 40 of the lever 38 and the screw 87 engages therewith so that by means of the set screw 85 and the set screw 87 adjustment of the two ends 40 and 82 of the lever 38 can be made independent of the cam 88 which engages 55 with the operative end 89 of the portion 82 of the lever 38 to operate the same. The portion 82 of the lever 38 is held by the coil spring 90 with the operative end 89 against the cam 88. This cam is carried by the shaft 17. The mandrel shaft 42 is notched as shown in Figure 7 to receive the plate 41. The forward end 40 bearing the plate 41 is normally pushed downward by the spring 55 which operates the mandrel rod 42. Thus when the set screw 87 is operated it provides a stop against the rear portion 40 of the lever 38 and together with the adjusting screw 87 the relation between the ends 40 and 82 of the lever 38 is adjusted so that the operating end plate 41 for operating the eyelet setting plunger 23 and the mandrel 42 may be adjusted in relation to the 70 75

cam 88. This provides a very fine or virtually micrometer adjustment to the operating end of the eyelet plunger sleeve 23 and the mandrel 42.

In the operation of my machine to punch a hole and set the eyelet or other similar means, the sliding plate 11 which carries the motor and the operating head 20 with the eyelet mandrel and the punch, are normally held by the coil spring 91 which is positioned under the bed in backward position, as illustrated in Figure 7. When the motor A is operated the punch plunger 33 is first operated by the cam 24 to punch the hole in the stick C. In the operation of the motor A the lever 76 is operated simultaneously with the starting of the motor A which clamps the stick C between the rests 73 and the fingers 75 while the hole is punched. Just before the hole is punched the cam 92 which is carried on the shaft 17 operates the lever 93 which is pivoted at 94 to the under portion of the bed 10 and the working end 95 of the lever 93 operates the lever 96 which is pivoted at 97 to cause the end 98 of the lever 96 to engage under the punch anvil 37 to raise the punch anvil 37 sufficiently to bring the punch anvil up against the stationary stick C.

In the punching operation the operation of the cam 92 engages with the working end 99 of the lever 93 while in the eyelet setting operation the cam 92 engages the working end 100 of the lever 93. After the hole has been punched by the punch 54 in the stick C the cam 101 which is carried by the shaft 17 operates against the stop or cam shoulder which projects upward from the base 10. When the cam 101 operates against this shoulder 102 it causes the sliding plate 11 to carry the motor and operating head 20 with the punch and eyelet setting means forward in position so as to carry the eyelet mandrel 42 directly above the hole which has been punched in the stick C. The bolt through the sliding plate 11 and the boss on the plate 11 to which the spring 91 is attached, which boss moves in a slot in the base 10, act to hold the slideable parts in alignment with the base 10. As hereinbefore set forth, when the punch 54 operates to punch the hole in the stick, the eyelet mandrel 42 picks up an eyelet 48. The mandrel 42 carrying the eyelet 48 is moved over the hole punched in the stick C and the lever 93 is again operated to raise the anvil 37 up against the lower portion of the stick C by the operating end 98 of the lever 96 and the continued operation of the eyelet setter rivets the eyelet through the stick C, while the parts are in this position, after which the cam 101 releases the mechanism carried by the plate 11 so that the spring 91 operates to pull the same back into the normal position ready to start to punch a hole in a new curtain stick.

The punch plunger sleeve 34 carries an adjustable shoulder dog 110 which is pivotally mounted on the collar 111 carried by the punch plunger sleeve 34 and movable therewith between the end 35 of the head 20 and the operating end 31 of the lever 27. This dog is adapted to operate to hold the sleeve 34 down into contact with the stick C while the punch 54 is being withdrawn from the stick C. As soon as the punch 54 is withdrawn from the stick the dog 110 is released by pressure of the upwardly moving end 31 of the lever 27 against the cam end 112 of the dog 110 so as to permit the sleeve 34 and the plunger 33 of the punch 54 to be raised together back into normal position. It may be seen that the sleeve 34 thus acts to strip the stock from the punch 33.

One end of the dog 110 is longer with respect 75

to the pivot therethrough than is the other, causing this end to drop when the lever 31 is moved downwardly, the shorter end of the dog 110 engaging against the lower surface of the end 5 35. The dog 110 holds the sleeve 34 down until the lever 31 moves against the cam edge of the dog 110, pivoting the dog 110 and allowing the dog to pivot. The punch plunger 33 is thus drawn into the sleeve 34 before this sleeve raises, 10 stripping the stick from the punch.

I provide spring stops 114 which are operated by the set screw 115 to move the stop end 116 which forms a gauge against which the stick may be set in placing the same in the machine 15 to set an eyelet therein. These spring gauges are carried by the base 10 and operate to provide two adjustable stops.

My eyelet and grommet setting machine operates automatically by an electric motor A. I provide a suitable wiring such as is illustrated diagrammatically in Figure 13 which shows the motor A connected with the power supply line 20 103. This circuit in Figure 13 shows an electric push button 104 which starts the motor A to operate. As soon as the motor A starts to operate a cam 105 carried by the shaft 17 which is illustrated diagrammatically in Figure 6, engages the cam end 106 of the lever 107 which is pivoted at 108 and causes the end 108 of the lever 107 to 25 30 pivot down across the contacts 109. This closes the circuit from the line 103 to the motor A, causing the motor A to operate until the cam 105 engages a wedge shaped projection on the cam end 106 of the lever 107 pivoting the lever into the position illustrated in Figure 6 to open the circuit at the contacts 109, causing the motor A to stop automatically at the proper time. The operation is automatic it being only necessary to 35 40 press the button 104 which is conveniently located in relation to the eyelet machine and before the operator's finger is removed from the button 104, the cam 105 has operated the lever 107 to cover the contacts 109, keeping the motor circuit closed with the line 103 to keep the motor operating, until my automatic electric eyelet and grommet machine has punched the hole and set the eyelet. This operation is accurate, the cam setting is adjustable and the entire operation quickly accomplished in a very simple and effective manner.

The method of supplying eyelets in the magazine form is also important as it overcomes any necessity for an eyelet hopper, holds the eyelets in alignment in a slide which also provides the magazine 49 and permits the eyelets to be easily handled and inserted in the eyelet machine. The accomplishment of my automatic electric eyelet and grommet machine provides a very desirable means for setting eyelets in curtain sticks and the like. It is not necessary that the operator be skilled because the operations are simple and effective and are automatic after the machine has started until it stops in completing the entire operation.

In accordance with the patent statutes I have described and illustrated my automatic electric eyelet and grommet machine and while the illustrations are drawn particularly to the setting of an eyelet for curtain sticks and the like, the same structure will operate to set grommets and other eyelets for various purposes, I desire to interpret the functions and operations of my electric eyelet machine within the scope of the following claims.

75 I claim:

1. An eyelet setter for curtain sticks including, means for clamping the curtain stick firmly in place, means for punching a hole in the stick, eyelet setting means, means for shifting the eyelet setting means to place an eyelet in the hole punched in the stick, means for moving the parts back to punching position, and an electric motor shiftable with said punching and eyelet setting means for operating said clamp, punch, eyelet setter, and shifting means. 5 10

2. A device for setting eyelets and grommets including, an electric motor, an operating head, a punch for punching a hole, an eyelet setter, an adjustable spring gauge against which the article to receive the eyelet is set, a clamp for holding the article, cushion means carried by said clamp to prevent injury in the clamping of the article, a centering means to center the article in relation to the punch and eyelet setting means, and lever and cam means for operating said clamp punch and eyelet setting means to automatically set an eyelet in the article held in said clamping means. 15 20

3. The combination, an electric motor, a punching element, lever and cam means for operating said punching element, a stripping element for said punch associated therewith, means for operating said stripping element, an eyelet pick-up setting and riveting means, lever and cam means for operating said eyelet pick-up setting and riveting means, and shifting means adapted to cause said punching means to be first placed in position to be operated and then said eyelet riveting means shifted into operable position. 25 30 35

4. The combination, a punch, an eyelet receiving and riveting means, shifting means to shift said punch and eyelet setting means from punching position to eyelet setting position, clamping means for holding the article being operated on, gauge means for setting the article centrally between its ends in relation to the punch and eyelet means, and an electric motor movable with said punch and riveting means by said shifting means for operating said punching, eyeleting and shifting means. 40 45

5. An automatic electric eyelet and grommet machine including, a punch for punching a hole, an eyelet setting plunger and mandrel, means for clamping a curtain stick, means for movably supporting said punch and eyelet setting plunger and mandrel as a unit to move the machine into eyeleting position after the hole has been punched in the clamped stick, and an electric motor movable with said punch and eyelet setting plunger for operating said machine. 50 55

6. An automatic electric eyelet and grommet machine including, an electric motor for operating the same, a punch for punching the hole, an eyelet setting plunger and mandrel, levers for operating said punch and plunger, a supporting frame for said punch, said plunger, said mandrel and said operating levers, means for supporting a curtain stick, and means for movably supporting said frame and means for moving said frame to move said punch and said plunger successively over the curtain stick. 60 65

7. An automatic electric eyelet and grommet machine including, an electric motor for operating the same, a punch for punching a hole, an eyelet setting plunger and mandrel, means for supporting a curtain stick in position to be punched and eyeleted, and a pair of spring stops for aligning said stick in the proper position. 70 75

8. An eyelet and grommet machine including, a base, a movable plate mounted upon said base, 75

a punch and an eyeleting plunger mounted upon said plate, an electric motor for operating said punch and plunger, said motor being mounted on said movable plate, means for supporting a curtain stick stationary with respect to said base, and means for moving said movable plate on said base to place the same first in position to punch a hole through said stick and then to clinch a rivet in said hole.

9. An eyelet and grommet machine including, a base, a movable plate mounted on said base, a punch, a plunger and mandrel, means for operating said punch to punch a hole in a curtain stick, means for moving said eyelet setting plunger in eyeleting position, means for raising said plate, and an anvil adapted to bear against said curtain stick when said plate is raised to clinch an eyelet.

GEORGE T. BIGGS.
